PADLOCK

Filed Feb. 29, 1928

UNITED STATES PATENT OFFICE.

WILLY W. WERNER, OF DETROIT, MICHIGAN.

PADLOCK.

Application filed February 29, 1928. Serial No. 257,854.

This invention relates to improvements in padlocks and refers particularly to padlocks having a U-shaped holding member one leg of which is adapted to be released from the body of the lock when the key is turned to unlocked position so that the holding member may be turned pivotally about the axis of its second and longer leg.

It is an object of the invention to provide a padlock wherein, as soon as the key is turned to unlocked position, the U-shaped member is automatically moved outwards from the body until its shorter leg is released so that the longer leg may be turned about its own axis.

Another object of the invention is to provide a padlock from which the key may be removed when the U-shaped member is in open position, that is with its shorter leg disengaged from the body of the lock.

A further object of the invention is to provide a padlock wherein both legs of the U-shaped member are simultaneously and automatically gripped and held immovable when they have been moved a predetermined distance into the body of the lock irrespective of whether the key is in locked or unlocked position when the movement is commenced.

With these and other objects in view, the invention, which consists in certain novel construction and combination of parts, is hereinafter more fully described with the aid of the accompanying drawings, in which:

Figure 1 illustrates a perspective view of the invention.

Figure 2 shows a sectional view of the padlock in locked position, and

Figure 3 is a section on the line 3—3 of Figure 2.

Figure 4 is a sectional view showing the padlock in unlocked position, and

Figure 5 shows a section on the line 5—5 of Figure 4.

Referring to the drawings, 1 designates the body of a padlock having a longer and a shorter passage 2 and 3, substantially parallel with one another, extending therein from one side; the passage 2 receives a longer leg 4 of the U-shaped holding member 5 and the passage 3 receives the shorter leg 6 thereof. Substantially centrally between the passages 2 and 3 and parallel with them is a cylindrical cavity 7 having a plunger 8 therein which latter has an annular

groove 9 intermediately of its length. 10 and 11 indicate apertures extending between the cavity 7 and the passages 2 and 3 respectively. In these apertures 10 and 11 are locking members 12 and 13 respectively. The end of the aperture 11 adjacent to the passage 3 is reduced as also is the outer end of the locking member 13 so as to prevent the latter from falling into the passage 3 when the said passage is not occupied by the shorter leg 6 of the holding member. The legs 4 and 6 are provided with opposed recesses 14 and 15 on their inner sides which are engaged by the outer ends of the locking members 12 and 13 when the padlock is in locked position as shown in Figure 2. 16 indicates an annular groove around the leg 4 towards its extremity, of lesser depth than the recess 14, against a portion of which the locking member 12 bears when the padlock is in open position shown in Figure 4. 17 is a flat extending longitudinally along the leg 4 from the recess 14 to the annular groove 16 and substantially the same depth as the latter.

18 designates a cylinder mounted in the body of the lock having a revolvable plug 19 therein, the axis of which latter is substantially at right angles to the axis of the cavity 7. 20 designates a locating pin which passes through an opening 21 in the body usually extending from the bottom of the passage 3, through a hole 22 in the cylinder, thereby holding the latter immovable in the body, and terminates in a segmental slot 23 in the plug so that the turning movement of the latter is limited. 24 and 25 indicate the usual tumbler pins and tumbler extensions in the plug and cylinder respectively, and 26 are the usual springs which tend to force the said pins into the plug. A keyslot 27 is provided in the plug for a conventional key 28. The inner end of the plug is substantially semi-circular in section and is located under one end of the plunger 8. The opposite end of the latter is preferably tubular, as indicated at 8^a, to receive one end of a spring 29 the opposite end of which bears against the adjacent end of the cylindrical cavity 7. This spring tends to force the plunger against the end 19^a of the plug 19.

The end 4^a of the longer leg 4 is also tubular to receive one end of a helical spring 30, the opposite end of which latter rests against the bottom of the passage 2, and is

adapted to exert upward pressure on the holding member and should be of sufficient strength to raise the said member sufficiently to disengage the shorter leg 6 from the passage 3.

Briefly the operation of the padlock is as follows: When the plug 19 is turned from the position shown in Figures 2 and 3 to that shown in Figures 4 and 5 the semi-circular portion 19^a thereof raises the plunger 8 against the tension of the spring 29. The locking members 12 and 13 are then free to move inwardly so that their adjacent ends engage the opposite sides of the annular groove 9, and this they do on account of the tension of the spring 30 exerted against the extremity of the longer leg 4. This spring causes the holding member to move outwards until the shorter leg 6 is clear of its passage 3 and until the annular groove 16 around the longer leg 4 is engaged by the outer end of the locking member 12. This groove 16 and the flat 17 on the leg 4 are so positioned that the locking member 12 cannot move sufficiently outwards for the spring 29 to move the plunger 8, so that the latter must remain stationary until the holding member is returned to locking position and the recesses 14 and 15 are opposite the locking members 12 and 13.

Therefore if the plunger 19 is returned to the position shown in Figures 2 and 3 and the key 28 removed, or if the plug is left in the position shown in Figures 4 and 5 and the key left in its slot, the replacement of the holding member will cause the locking mechanism to function. For in the latter case the spring 29 is strong enough to force the plunger 8 downwards against the plug end 19^a in such a manner as to turn the latter. In order to facilitate such movement it will be noted that the plug movement is so limited that the semi-circular portion 19^a cannot assume a quite vertical position, that is a position quite parallel with the axis of the plunger.

While in the foregoing the preferred embodiment of the invention has been described and shown it is understood that the construction is susceptible to such modifications as fall within the scope of the appended claims.

What I claim is:

1. In a padlock, a body having two substantially parallel passages therein and a cavity between said passages substantially parallel with them, said body having apertures therein connecting said cavity with said passages, a plunger in said cavity having an intermediate annular groove around it, a plug rotatable in said body having its axis substantially at right angles to the axis of said plunger, said plug being adapted to move said plunger so that its annular groove is opposite said apertures, and locking members movable in said apertures the outer ends

of which are adapted to project into said passages and the inner ends of which are adapted to engage said annular groove, in combination with a holding member having legs slideable in said passages, opposed recesses formed in the inner sides of said legs adapted to be engaged by said locking members when said padlock is in locked position, and means adapted to move said plunger so that its annular groove is not in line with said locking members when said leg recesses are aligned with the latter.

2. In a padlock, a body having two substantially parallel passages therein and a cavity between said passages substantially parallel with them, said body having apertures therein connecting said cavity with said passages, a plunger in said cavity having an intermediate annular groove around it, a plug rotatable in said body having its axis substantially at right angles to the axis of said plunger, said plug being adapted to move said plunger so that its annular groove is opposite said apertures, and locking members movable in said apertures the outer ends of which are adapted to project into said passages and the inner ends of which are adapted to engage said annular groove, in combination with a holding member having legs slideable in said passages, opposed recesses formed in the inner sides of said legs adapted to be engaged by said locking members when said padlock is locked, and means adapted both to move said plunger so that its annular groove is not aligned with said locking members and to turn said plug when said leg recesses are aligned with said locking members.

3. In a padlock, a body having two substantially parallel passages therein and a cavity between said passages substantially parallel with them, said body having apertures therein connecting said cavity with said passages, a plunger in said cavity having an annular groove around it intermediate of its length, said plunger being movable so that its annular groove may either be opposite said apertures or not, locking members in said apertures the inner ends of which are adapted to engage said annular groove, and a plug rotatable in said body having its axis substantially at right angles to said plunger adapted to move the latter so that its annular groove is opposite said apertures, in combination with a holding member having legs slideable in said passages, one of said legs being longer than the other, opposed recesses formed in the inner sides of said legs adapted to receive the outer ends of said locking members to hold said holding member immovable, and means adapted to move said holding member outwardly until the shorter leg is clear of said body when said plunger is so moved that its annular groove is opposite said locking members.

4. In a padlock, the combination as described in claim 3 wherein means are provided for preventing the locking member adapted to engage the shorter leg from falling into the passage in which said leg is movable.
5. In a padlock, the combination as described in claim 3 wherein means are provided for preventing movement of said plunger when the longer leg of the holding member is being moved in its passage.
6. In a padlock, a body having two substantially parallel passages therein and a cavity between said passages substantially parallel with them, said body having apertures therein connecting said cavity with said passages, a plunger in said cavity having an annular groove around it intermediate of its length, a means for moving said plunger so that its groove is opposite said apertures, means for moving said plunger so that its groove is not opposite said apertures, locking members in said apertures the inner ends of which are adapted to engage said annular groove, in combination with a holding member having a longer and a shorter leg each slideable in one of said passages, opposed recesses formed in the inner sides of said legs adapted to be engaged by said locking members when the annular plunger groove is not opposite said apertures, means for moving said holding members outwards until the shorter leg is clear of its passage, means on said longer leg for holding its adjacent locking member against movement as said holding member moves or when it is outstretched, and means for preventing disengagement of said longer leg, said holding member being rotatable about the axis of said longer leg when the shorter leg is disengaged from its passage.
7. In a padlock, a body having two substantially parallel passages therein and a cavity between said passages substantially parallel with them, said body having apertures therein connecting said cavity with said passages, a plunger in said cavity having an annular groove around it intermediate of its length, a plug rotatable in said body, a portion of said plug being adapted to engage said plunger and move it so that its annular groove is opposite said apertures, the opposite end of said plunger being tubular, a spring seated partly in said tubular end tending to move said plunger so that its annular groove is out of alignment with said apertures, locking members movable in said apertures the inner ends of which are adapted to engage said annular groove and the outer ends of which are adapted to extend into said passages, in combination with a holding member having a longer and a shorter leg one of which is slideable in each of said passages, opposed recesses formed in their inner sides adapted to receive the outer ends of said locking members, a spring bearing against the extremity of said longer leg adapted to move said holding member outwardly when said locking members move inwardly from said recesses, and means for holding said plunger so that its annular groove remains opposite said apertures during the movement of said holding member.
8. In a padlock, a body having two substantially parallel passages therein and a cavity therein parallel with said passages, said body also having apertures therein each connecting said cavity with one of said passages, a plunger movable longitudinally in said cavity having an intermediate annular groove around it, means for moving said plunger, and locking members in said apertures adapted to be moved by the movement of said plunger as they engage and disengage said annular groove, in combination with a substantially U-shaped holding member the ends of which are slideable in said passages, and said member ends having recesses therein adapted to receive said locking members and to be held against movement in their passages thereby.
9. In a padlock, a body having two substantially parallel passages therein and a cavity between said passages, said body also having apertures therein each connecting said cavity with one of said passages, a plunger in said cavity having an intermediate annular groove around it, means for moving said plunger longitudinally so that its annular groove is brought opposite said apertures, other means for moving said plunger so that its annular groove is no longer opposite said apertures, and locking members in said apertures, in combination with a holding member having legs slideable in said passages, and opposed recesses formed in said legs adapted to be engaged by said locking members.
